(57) **CLAIM**

The ornamental design for a pet gate as shown and described.

DESCRIPTION

FIG. 1 is a front perspective view of a pet gate, showing my new design;

FIG. 2 is a front elevational view thereof, the rear elevational view is identical;

FIG. 3 is a left elevational view thereof, the right side view is identical;

FIG. 4 is a top plan view thereof;

FIG. 5 is a bottom plan view thereof;

FIG. 6 is an enlarged view of the portion outlined and labeled "6" in FIG. 1;

FIG. 7 is an enlarged view of the portion outlined and labeled "7" in FIG. 1; and,

FIG. 8 is a front perspective view of the pet gate in a folded state.

The long-dash dot lines in FIGS. 1, 6, and 7 represent boundaries for the enlarged views shown in FIGS. 6, and 7, and form no part of the claimed design.

1 Claim, 6 Drawing Sheets
